Des. 183,305
Patented Aug. 5, 1958

183,305

ILLUMINABLE INSPECTION UNIT FOR AIRPLANES OR THE LIKE

Lorin R. Fisher, Wichita, Kans.

Application October 3, 1956, Serial No. 43,226

Term of patent 14 years

(Cl. D57—1)

Fig. 1 is a perspective view of an illuminable inspection unit for airplanes or the like illustrating my new design;
Fig. 2 is a side elevational view thereof.

I claim:

The ornamental design for an illuminable inspection unit for airplanes or the like, as shown.
